ARTICLE OF FURNITURE

Harry Lon Ross, Philadelphia, Pa.

Application March 28, 1936, Serial No. 71,487

6 Claims. (Cl. 155—123)

This invention relates to improvements in articles of furniture, being particularly directed to a table and chair assembly, of the folding type. Broadly, it is an object of this invention to provide a table and chair assembly wherein a rack or guide rail formation is formed within the confines of the table for supporting and maintaining the chairs therein when the latter are not in use; the table being so formed and the rack assembly therein being so disposed as to substantially conceal the chairs when maintained therein, except at the ends.

Another object of this invention is to provide a table and chair assembly which, by its novel construction, may be folded to approximately half its width, with means applied to the under-surface of the side leaves, or the top, to receive and support the several folding chairs when such assembly is not being used. Such table and chair combination is extremely useful and adaptable to meet the demands of modern apartments, game rooms, sun porches, and the like, where storage space is at a premium, since said table and chair assembly may be so folded into a single or self-contained unit, and at the same time present an attractive piece of furniture when such is not being used for card playing or dining.

Specifically, it is an object of this invention to provide for a table wherein a plurality of guide rails or track formations are disposed on the under-surface of the side leaves for supporting or maintaining folded chairs in a horizontal position when not in use. The table may be constructed in a modified form, whereby hooks or said guide rails are disposed beneath the flat top of said table so that the folded chairs may be suspended in a vertical position.

These objects and others, such as economical construction, strength and lightness of structure and pleasing appearance, are accomplished by the novel construction, combination and arrangement of parts hereinafter described and illustrated in the accompanying drawings, constituting a material component of this disclosure, and in which

Figure 1 is a perspective view of a table and group of associated chairs as arranged for individual service.

Figure 2 is a similar view of the same, the chairs being folded and secured within the confines of the table to be moved as a unit.

Figure 3 is another like view of the device, the chairs being attached in a modified manner.

Figure 4 is an end elevational view of the device as shown in Figure 2.

Figure 5 is a longitudinal sectional view taken on line 5—5 of Figure 4.

Figure 6 is a fragmentary sectional detail view taken on line 6—6 of Figure 4.

Figure 7 is a perspective view of the toggle joint levers for supporting the table side leaves.

Figure 8 is a fragmentary sectional view taken on line 8—8 of Figure 7.

Figure 9 is a similar sectional view of the leaf retaining latch and connections.

Figure 10 is a transverse sectional view of the device shown in Figure 3.

Referring in greater detail to the drawings, the table or stand is shown to be composed of a main top 15 and a pair of side leaves 16 connected by hinges 17 at their lateral edges.

These hinges may preferably be of the lock type, whereby the sides are held firmly when folded downwardly and also when extended level with the surface of the fixed top 15 to form substantially a rectangular flat surface.

The table legs are of tubular construction, consisting of spaced apart level feet 18, extending longitudinally of the table and adapted to rest upon a floor or equivalent surface, having upwardly curved ends blending into upright legs 19 connected by cross members 20 disposed adjacent the ends of the top element 15 and connected rigidly to its ends by lugs 21 welded or otherwise fixed to the cross tubes and provided with straps 22 held by screws or like fastenings to the underside of the table top, as best seen in Figures 5 and 6.

The sides 16 are held rigidly when raised by pairs of toggle joint levers 24—25, see Figure 7, the levers 24 being attached by pivot screws 26 to the legs 19.

The mating levers 25 are pivoted at 27 to angular brackets 28 fixed on the under surface of the sides 16, and connected by pivots 29 to the outer ends of the levers 24, which rest on in-turned flanges 30 at the inner, lower extremities of the levers 25, the arrangement being such as to afford an efficient support for the table sides which can only be released by lowering the levers 25 at a point adjacent the pivots 29.

In order to retain the sides 16, when hanging pendant, from inadvertent movement, notches 32 are formed in their lower inner corners to receive latches 33, pivoted at 34, in the legs 19, these latches being normally forced outwardly through openings 35 in the legs, see Figure 9, by compression springs 36 and are manually retractable when it is desired to extend the sides.

In the form of table shown in Figures 1, 2, 3 55

and 4, a series of rods 37 are provided with feet 38 held by fastenings 39 to the inner surfaces of the sides 16, these rods being uniformly spaced and level, constituting in effect, pairs of 5 opposed shelves or rack assembly.

The chairs, preferably four in number, consist of seats 40, supported at their sides, near the front by rearwardly inclined tubular legs 41, connected thereto by pivots 42 and provided with 10 cushioned feet 43 at their lower ends. The seat 40 of each chair is pivotally and slidably connected to the rear legs 44 in any well known manner.

The rear legs 44 have similar terminals at their 15 lower ends and extend upwardly at an angle above the level of the seats 40.

The upper ends of the rear legs are integrally united by a cross piece 45, from which depends a flexible cushion 46, the lower end edge of which 20 engages a cross strap 47.

The front legs are cross connected by straps 48 and are pivoted at 49 to rear legs 44 at their points of intersection.

Thin rods 50 engage at their upper ends with the 25 ends of the straps 47 to extend in close relation to the rear legs, nearly to their bottoms, to which they are secured.

It will now be seen that the chairs are readily collapsed and foldable into a thin flat position, 30 easily insertible within the spaces formed by the shelf rods 37 to rest securely thereon, when the sides 16 are folded downwardly and secured in such position by the latches 38.

In the modification shown in Figures 3 and 10, 35 in place of the support rods as previously described, a series of hooks 55 are fixed in rows under the main top 15 of the table, and the chairs suspended by engaging the rods 50 directly on the hooks, permitting the chairs to hang pendant.

40 It is to be understood that the construction of the chairs is immaterial, as any type of chair capable of being flat folded, may be used, the chairs being suspended below the main table top and held securely within the confines of the folded leaves.

45 The foregoing disclosure is to be regarded as descriptive and illustrative only, and not as restrictive or limitative of the invention, of which obviously an embodiment may be constructed including modifications without departing from the 50 general scope herein indicated and denoted in the appended claims.

Having thus described the invention, what is claimed as new and desired to secure by Letters 55 Patent, is:

1. A table comprising a top, side leaves hinged to the table top, the latter forming when disposed horizontally with the top, a rectangle of equal length and width, tubular legs connected to the 60 ends of said top, spaced pairs of toggle joint levers attached to said legs and the respective side leaves to support said leaves when raised, said leaves having notches in the outer ends, spring impelled latches pivoted in said legs to engage the notches when said leaves hang pend-

ant, thereby to retain them rigid, and tiers of spaced rods fixed on the under surfaces of said leaves to extend longitudinally thereof, said rods acting as shelves to support folded seats entered therebetween in collapsed condition when the 5 leaves are disposed vertically.

2. A table comprising a unitary flat top, legs extending downwardly from the table top, side leaves hinged to said top, means to support said leaves when extended horizontally, other means 10 to retain said leaves when positioned vertically, and tiers of spaced tracks affixed to the under surfaces of said leaves to extend longitudinally thereof, said tracks acting as shelves to engage and support folded chairs placed therebetween, 15 when the leaves are disposed vertically.

3. A table comprising a top including a central stationary section and side leaves hingedly connected thereto, supporting legs extending downwardly from the stationary section, means for 20 supporting the hinged side leaves in a raised horizontal position, coacting track forming members arranged on the underside of the hinged leaves for slidably receiving and supporting a folded chair when the leaves are disposed in a lowered 25 vertical position, and additional means for holding the table leaves from swinging outwardly when said leaves are disposed vertically.

4. A table comprising a top including a central stationary section and side leaves hingedly connected thereto, supporting legs extending downwardly from the central stationary section, means for supporting the hinged side leaves in a raised 30 horizontal position, coacting pairs of tracks arranged longitudinally in spaced relation on the 35 underside of the hinged leaves acting as shelves for receiving and supporting a plurality of folded chairs that are insertible on said tracks from the end of the table, when the hinged leaves are disposed in a lowered vertical position, and additional means for holding the table leaves from swinging outwardly when said leaves are disposed vertically. 40

5. A table comprising a top including a central stationary section and side leaves hingedly connected thereto, supporting legs extending downwardly from the central stationary section, means for supporting the hinged side leaves in a raised 45 horizontal position, and means on the inner faces of the hinged leaves for receiving and supporting a folded chair in a generally horizontal position when said leaves are disposed vertically. 50

6. A table comprising a top including a central stationary section and side leaves hingedly connected thereto, supporting legs extending downwardly from the central stationary section, means for supporting the hinged side leaves in a raised 60 horizontal position, and means on the inner faces of the hinged leaves for receiving and supporting a folded chair in a generally horizontal position when said leaves are disposed vertically and means for locking the leaves against movement relative to each other. 65

HARRY LON ROSS. 6
